W. C. RASTETTER

FOLDING CHAIR

Filed Oct. 6, 1924

William C. Rastetter INVENTOR

BY

H. G. Burns ATTORNEY

UNITED STATES PATENT OFFICE.

WILLIAM C. RASTETTER, OF FORT WAYNE, INDIANA.

FOLDING CHAIR.

Application filed October 6, 1924. Serial No. 741,829.

To all whom it may concern:

Be it known that I, WILLIAM C. RASTETTER, a citizen of the United States of America, and resident of Fort Wayne, in the county of Allen and State of Indiana, have invented certain new and useful Improvements in Folding Chairs, of which the following is a specification.

This invention relates to improvements in folding chairs and the object thereof is to provide a sliding connection between a folding seat and the supporting structure of the chair that is operable as a clamp to hold the seat and support therefor rigidly together when the chair is in position for use.

This object is accomplished by the construction illustrated in the accompanying drawings, in which:—

Fig. 1 is a side elevation of a chair embodying the invention;

Fig. 2 is a front elevation projected from Fig. 1;

Fig. 3 is a detail showing the sliding connection between the seat and prop, viewed from the rear of the seat; and

Fig. 4 is an elevation projected from Fig. 3.

The characters appearing in the description refer to parts shown in the drawings and designated thereon by corresponding characters.

The invention comprises a main frame 1 having parallel legs 2, the lower ends of which are connected by a cross-piece 4 and brace 5. Supported horizontally between the legs is a rod 6 upon which is pivotally mounted a seat 7 having a rearwardly extending projection 8 at each side thereof, and a U-shaped prop 9 formed of a rod bent so as to have upwardly extending arms 10, has pivotal connections 11 at the ends of its arms respectively at points in the frame above the seat.

A shackle is positioned on each extension 8 and consists of a ring 12 that encompasses the extension and the adjacent arm 10 of the prop, that portion 13 of the ring that extends over the arm being arched and inclined rearwardly from the bottom of the extension on the seat to the top thereof. Each shackle is secured upon the corresponding extension by any suitable means such as a staple 14 placed astride the ring and driven into the extension.

A back 15 is secured at its top within the frame and has a sliding connection 16 at its

lower end with the corresponding arms 10 of the prop. Also, a brace 17 is pivoted on the rod 6 between each side of the seat and the corresponding leg of the frame, and has limited sliding movement on the corresponding arm 10 of the prop, which braces serve to sustain the prop in extended position.

In the operation of the invention the seat is swung upon the rod 6 to horizontal position, the prop being swung outwardly from the frame, as the seat is turned down, by reason of its engagement in the shackles on the seat. The upward movement of the shackles on the arms of the prop is limited by the binding action of the shackles on the arms which takes place when the seat is turned down to its position for use. Owing to the curvature of the portion 13 of the shackle, the arm 10 extending therethrough is forced tightly against the adjacent face of the extension when the binding stage is reached and thus the seat and the prop are held rigidly together when in operating position.

What I claim is:—

1. In a folding chair, a main frame; a seat pivotally supported in the frame and having a rearwardly extending projection at each side thereof; a prop member having arms pivoted respectively at their tops to the frame at points therein above the seat; a shackle member encompassing each of said projections and the corresponding adjacent arms of the prop member, and having limited sliding movement on said arms and being operable to clamp the arms against said projections when the seat is in position for use; a back secured at its top to the frame and having a sliding connection at its bottom with each of the arms of said prop; and a pivoted brace at each side of the seat having limited sliding movement on the corresponding arm of the prop.

2. In a folding chair, a main frame; a seat pivoted in the frame; each side of the seat having an extension at the rear end thereof; a prop member having arms pivotally attached at their respective upper ends to the frame at points therein above the seat; a shackle fixed on each side of the seat adjacent the rear end thereof and having a curved outer portion and encompassing the corresponding extension and the adjacent arm of the prop, each shackle being disposed upon an incline from the bottom of the extension in front of the arm to a

point at the top of the extension back of the seat; and a shackle fixed on each extension arm, and being operable to clamp the arm and having a curved outer portion and encompassing the said extension and the corresponding arm of the prop, each shackle being disposed upon an incline from the bottom of the extension in front of the arm to a point at the top of the extension back 15 20 of the arm, and being operable to clamp the arm against the side of the extension when the seat is in position for use.

3. In a folding chair, a main frame; a seat pivoted in the frame; and having a rearwardly projecting extension at each side thereof; a prop member having arms pivotally attached at their respective upper ends to the frame at points therein above the 10 15 20

In testimony whereof I affix my signature.

WILLIAM C. RASTETTER.
